HAIR CURLING DEVICE

William H. H. Davis and Floyd V. Schleimer, San Francisco, Calif.; said Schleimer assignor to Duart Manufacturing Co., Ltd., a corporation of California

Application January 8, 1949, Serial No. 69,932

1 Claim. (Cl. 132—39)

1

This invention relates to devices to be used in connection with the curling of hair and particularly to devices on which separate locks of hair may be tightly wound in Croquignole fashion and then secured in place for a considerable period of time in order to permit the hair to take a set in the form of a Croquignole curl or wave.

It is an object of this invention to provide a device of the character described which is relatively small and of simple and inexpensive construction, and which is easily used for the purpose intended by either a skilled beauty operator or in the home.

A further object of the invention is to provide a device of the character described which will be maintained in place by the hair which is wound thereon and which is so constructed that the device may be placed immediately adjacent the scalp, so that the entire lock, from its free end to the scalp, will receive a wave.

The other objects, features and advantages of this invention will be described in the following description taken in connection with the accompanying drawings in which:

Figure 1 represents a hair curling device upon which hair is to be wound.

Figure 2 represents a device, the device shown in Figure 1 in which substantially all of the hair has been wound.

Figure 3 shows the device in Figures 1 and 2 in which the entire lock has been wound thereon and the device has been positioned upon the scalp.

Figure 4 is a plan view, from above, of the device shown in Figure 3.

Figure 5 is a top view of the device shown in Figure 4, with the hair removed.

Figure 6 is a side elevational view, partly in cross-section taken along the line 6—6 of Figure 5.

Figure 7 is a top view of a modification of the device shown in Figures 1 to 6 inclusive.

Figure 8 is a cross-sectional elevation taken along the line 8—8 of Figure 7.

As shown in the drawings, the device consists generally of a revolving mandrel 10 and a stationary shuttle 11.

The revolving mandrel 10 is provided with a knurled portion 12 which may be grasped by the user or operator and a portion 13 upon which the hair is adapted to be wound. As shown in the drawings the portion 13 is gently tapered. However, as is well known to those skilled in the art of waving hair, the mandrel 13 may be either

straight or tapered, in accordance with the types of curl or wave desired.

The stationary shuttle 11, as shown in the drawings, forms a base upon which the revolving mandrel 10 is mounted, and also provides means for gripping the wound hair. As shown in Figures 4 and 5, the shuttle 10 is provided with an opening 16 and a pair of identical slots 17 and 18. In addition, the shuttle 11 is provided with a flattened side 19, the purpose of which will be more fully hereinafter described.

The mandrel 10 and shuttle 11 may be joined in any suitable manner and we have shown two suitable ways in Figures 6 and 8.

15 In Figure 6 shuttle 11 is provided with a centrally located orifice adapted to accommodate an enlarged end of the mandrel 10. Mandrel 10, in turn, is provided with an extension 21 and shuttle 11 is cut away slightly to accommodate

20 a washer 22. Between the washer 22 and the shoulder 23 on the mandrel 10, provided by the extended portion 21, we have placed a washer 24 formed of some readily deformable material such as natural or synthetic rubber. The member 21 is then flattened, as is well known to those skilled in the art and in much the same manner as a rivet is spread, over the washer 22 thereby permanently securing the members 10 and 11 together and slightly deforming the member 24.

25 30 By virtue of deforming the member 24, the members 10 and 11, while adapted to be rotatable with respect to each other, are not freely rotatable in the true sense. In other words, when hair has been wound upon the mandrel 10 and the device has been locked to the scalp as shown in Figures 3 and 4, the tension of the hair will not unwind the mandrel 10 with respect to the shuttle 11.

Another means of securing the mandrel 10 to

40 the shuttle 11 is shown in Figure 8 in which the shuttle 11 is provided with a centrally located cut-away portion 26 which is adapted to accommodate an enlarged annular flange 27 on the mandrel 10. As is shown the mandrel 10 is

45 hollow for some distance throughout its length and is provided with a central orifice 28 which is in register with a corresponding orifice 29 in the shuttle 11. A rivet 31 is adapted to pass through the orifices 29 and 28 into the hollow cavity 32 within the mandrel 10. A washer of some readily deformable material such as natural or synthetic rubber such as washer 33 is first placed around the rivet 31 after which a metal washer 34 is placed above the member 33 and the rivet 31 is flattened. In this way a free turning

of the member 10 with respect to the member 11 is prevented in the same manner as heretofore described in connection with the device shown in Figure 6.

Operation of the device may be briefly described as follows. A tress or strand of hair is separated from the remainder of the hair on the head and that end of the tress remote from the scalp is placed in contact with the portion 13 of the mandrel 10. The hair may be caused to adhere to the portion 13 either by the application of an end paper as is conventionally used in the trade or, merely by the tendency of the hair to adhere to the portion 13. It will be borne in mind that during waving operations the hair is normally wet or damp whereby its tendency to adhere or cling to the portion 13 is increased.

In order to facilitate the starting of the curl upon the member 13 it will be recalled that we have provided a cut-away portion 19 on the shuttle 11. In this manner the thumb or finger of the operator may be brought into position adjacent the mandrel 10 and portion 13 to enhance the ease with which the tress is wound upon the mandrel 10. By continually revolving or rotating the mandrel 10 the hair is wound from its ends towards its roots upon the same. As the mandrel 10 and the shuttle 11 are brought close to the scalp the device is tilted as generally shown in Figure 2 in such a manner that the tress which is being wound is caused to pass through the opening 16 into one of the slots 17 or 18. The device then assumes the position as shown in Figure 3 with respect to the scalp. Since the mandrel 10 and the shuttle 11 are rotatable with respect to each other the mandrel 10 may be rotated after the shuttle 11 is brought in engagement with the scalp and the tress of hair is firmly held within either the slot 17 or 18. In this manner the curl upon the mandrel may be tensioned as desired.

When the hair has dried and a curl has been imparted thereto the foregoing operations need not be reversed in entirety. It is sufficient if the mandrel is rotated approximately one revolution in the direction opposite to that in which the hair is wound. In this manner the hair is loosened from the mandrel. The tress may then be removed from either the slots 17 or 18 and the mandrel may be removed from the wound tress simply by passing it downwardly through the tress, or by moving it to the right as viewed in Figure 2.

In the modification shown in Figure 7 I have provided slots 17a and 18a which, it will be noted, are of irregular form. It has been found that by virtue of the irregular contour of the slots, they will engage the hair in such a manner that the same is not readily removable therefrom. This feature is of value when the person to whose hair the devices are applied wishes to have freedom of movement.

While many devices have been proposed by others in the past to achieve the results which we achieve, we have found that none of them are 65

satisfactory for various reasons. We have found it desirable to have a device upon which the hair may be tensioned even after the hair has been wound upon the device and the device has been placed in proximity to the scalp. No other device of this character has been made, to our knowledge. The combination of the rotating mandrel and the stationary shuttle make this possible. In the second place we have provided a device which may be secured to the hair without the use of pins, clips, or other devices. However, the slots 17 or 18 which we have provided, in and of themselves, would not achieve the result desired for the reason that if the hair were merely passed into the slot on the shuttle 11 without provision for further tightening of the hair or winding of the hair upon the mandrel 10, the device would not be retained upon the scalp.

Therefore it is readily seen that the combination of the rotating mandrel and the stationary shuttle is of utmost importance. Not only does it make possible further tensioning of the hair after the device has been applied to the hair and scalp but it also renders possible the use of a simple slot or pair of slots in the shuttle to retain the device upon the scalp. This feature eliminates the use of various types of caps, pins, clips, etc. which have been used in the past.

We claim:

30 In hair curling device, an outwardly tapered mandrel, a relatively flat base member disposed at one end of the mandrel at right angles to the axis of the mandrel and extending outwardly from the same for at least twice the diameter of the 35 mandrel, means serving to attach the base member to the mandrel for relative rotation between the parts about the axis of the mandrel, an annular ring of resilient material positioned between said base member and said mandrel providing friction means tending to impose a frictional restraint against such relative rotation, and oppositely faced arcuate slots formed adjacent the periphery of said base member to receive a strand of hair near its root end to thereby enable said 40 device to be held firmly adjacent the scalp.

WILLIAM H. H. DAVIS.
